Primary Examiner—Robert M Spear*Assistant Examiner*—Susan E Krakower(74) *Attorney, Agent, or Firm*—Buchanan Ingersoll & Rooney PC(57) **CLAIM**

An ornamental design for a rosary, as shown and described.

DESCRIPTION

FIG. 1 is a perspective view of my rosary;

FIG. 2 is a front elevation thereof;

FIG. 3 is a rear elevation thereof;

FIG. 4 is a top plan view thereof;

FIG. 5 is a bottom plan view thereof;

FIG. 6 is a right side view thereof;

FIG. 7 is a left side view thereof;

FIG. 8 is a perspective view of a second embodiment showing the rosary with a split in the ring;

FIG. 9 is a front elevational view showing the rosary with the split in the ring as in FIG. 8;

FIG. 10 is a rear elevational view showing the rosary with the split in the ring as in FIG. 8; and,

FIG. 11 is a top plan view similar to FIG. 4 showing the rosary with the split in the ring as in FIG. 8.

The bead which travels around the ring of the rosary and the text indicating position shown in broken lines, represent environmental structure and form no part of the claimed design.
